(No Model.)

C. DUBOIS.
PRESSURE REGULATOR.

No. 400,553.

Patented Apr. 2, 1889.

UNITED STATES PATENT OFFICE.

CHARLES DUBOIS, OF LEADVILLE, COLORADO.

PRESSURE-REGULATOR.

SPECIFICATION forming part of Letters Patent No. 400,553, dated April 2, 1889.

Application filed October 20, 1888. Serial No. 288,679. (No model.)

To all whom it may concern:

Be it known that I, CHARLES DUBOIS, of Leadville, in the county of Lake and State of Colorado, have invented a new and Improved 5 Pressure-Regulator, of which the following is a specification, reference being had to the annexed drawings, forming a part thereof, in which—

Figure 1 is a side elevation of my improved 10 pressure-regulator. Fig. 2 is a longitudinal section taken on line $x-x$ in Fig. 1. Fig. 3 is a transverse section taken on line $y-y$ in Fig. 2. Fig. 4 is a side elevation, partly in section, 15 of the valve-adjusting cap. Fig. 5 is a side elevation of the valve, showing the packing-ring in section; and Fig. 6 is a side elevation of the packing-ring.

Similar letters of reference indicate corresponding parts in all the views.

20 The object of my invention is to provide a simple and efficient valve for regulating the pressure of steam or air.

My invention consists in the combination, 25 with the valve-casing provided with inlet and outlet apertures, of a hollow piston-valve having a spiral port extending through its walls, a spring arranged to bear upon the piston-valve, and a valve-operating cap connected with the valve-spindle, all as hereinafter more 30 fully described.

The casing A, which is of cylindrical form, 35 is made in two diameters, and is divided transversely by a centrally-apertured partition, a , into the chambers b c . The end of the chamber c is closed by a screw-cap, d , in which is 40 inserted the stop-cock e . In the side of the casing A is formed an aperture, f , communicating with the chamber c , near one end thereof, and to the chamber c is fitted a chambered piston-valve, B, which is open at the end adjoining the cap d and closed at the opposite end. In the wall of the valve B is formed a spiral slot, g . The parts of the valve separated by the slot are braced by a connecting- 45 bar, h . Around the closed end of the valve B is formed a groove, i , in which is inserted a spring-packing, j . The valve B is provided with a shank, k , to which is jointed a square spindle, l , which extends through the apertured partition a . Between the closed end of the valve B and the partition a is placed a spiral spring, C.

In the chamber b is inserted the cylindrical part m of the cap D. The said cylindrical part m of the cap is provided with a circumferential groove, n , for receiving the end of the retaining-screw o , which extends through the wall of the casing A, and retains the cap D in its place in the casing. The cap D is provided with a rim, p , which extends over 55 the end of the casing A, and a short distance along the side thereof, and is graduated. The casing A is provided with a mark, q , for convenience in adjusting the cap D.

Steam or air under pressure is admitted 60 through the stop-cock e into the interior of the valve B. The pressure of the steam forces the valve B forward until the spiral groove g is opposite the aperture f , when the steam or air will escape through the said groove or aperture. The amount of pressure required to cause the steam or air to escape from the casing in the manner described depends upon the position of the spiral groove g relative to the aperture f , the position of the groove being adjusted by turning the cap D. Sometimes the pressure is so great that it will carry the slot g of the cylindrical valve completely 65 beyond the aperture f , and a large amount of unnecessary steam or air would be held within 70 the valve. To obviate this I provide the casing A with a relief-groove, a' , for permitting the escape of air and steam from the body of the casing to the opening f . To provide a further means for carrying off the surplus 75 steam or air, I make a short longitudinal groove, e' , in the lower end of the stop-cock e , which groove is adapted to register with a groove, e^2 , passing partially through the inlet-pipe, when the stop-cock is turned in position, 80 as shown in Fig. 2. From this it will be seen that the unnecessary steam or air will pass upward through the groove e' and out through the groove e^2 ; but when the stop-cock is turned at right angles a steam-tight joint is formed. 85

Having thus described my invention, I claim as new and desire to secure by Letters Patent—

1. In a regulator, the combination, with the casing A, provided with the head d and opening f , of the valve B, having a spiral groove, g , adapted to register with the opening f , and the spiral spring C, bearing upon the valve to oppose its forward movement, substantially 90 as shown and described.

2. In a regulator, the combination of the casing A, having the partition *a*, chambers *b* *c*, and aperture *f*, the cap *d*, closing the chamber *c*, the chambered valve B, having the spiral slot *g*, the spring C, abutting against the partition *a* and resting upon the closed end of the valve B, the spindle *l*, and the cap D, substantially as specified.
3. In a regulator, the combination of the casing A, having the partition *a*, chambers *b* *c*, and aperture *f*, the cap *d*, closing the chamber

ber *c*, the chambered valve B, having the spiral slot *g*, and provided with the packing-ring *j*, the spring C, abutting against the partition *a* and resting upon the closed end of the valve B, the spindle *l*, and the cap D, provided with graduations on its periphery, substantially as specified. 15

CHARLES DUBOIS.
